COOLING SYSTEM FOR INTERNAL-COMBUSTION ENGINES.

964,542.

Specification of Letters Patent. Patented July 19, 1910.

Application filed December 3, 1909. Serial No. 531,133.

To all whom it may concern:

Be it known that I, THORMOD ODEE, a citizen of the United States, residing at Beloit, in the county of Rock and State of Wisconsin, have invented certain new and useful Improvements in Cooling Systems for Internal-Combustion Engines, of which the following is a specification.

In internal combustion engines the end of the cylinder in which compression and explosion occur is subjected to more heat than the opposite end; consequently the explosion end of the cylinder expands to a greater extent and the piston fits more loosely in said end of the cylinder than in its opposite end, which results in a loss of compression and power.

The object of this invention is to provide an improved cooling system for internal combustion engines, which is arranged to have a greater cooling effect upon the explosion end of the cylinder than upon its opposite end, so that the cylinder shall be kept uniform in size throughout its length at all times.

The invention also relates to the various other improvements and advantages herein-after set forth.

In the accompanying drawings, Figure 1 is a sectional view showing a cooling apparatus embodying my invention applied to the cylinder of an internal combustion engine, the base of the engine being broken away and the greater part of its mechanism being omitted. Figs. 2, 3 and 4 are sections on lines 2 2, 3 3 and 4 4, respectively, of Fig. 1.

The embodiment which I have chosen for the purpose of illustrating the invention herein comprises a jacket 1 surrounding the engine cylinder 2, said jacket in this instance being integral with the base 3 of the engine. The cylinder 2 may be removable from the jacket, if desired, in order to permit of replacing said cylinder in case it should accidentally become damaged. Within the jacket 1 is a partition 4 which separates said jacket into two compartments 1^a and 1^b, which may be termed a forward compartment and a rear compartment, respectively.

The means for holding the cylinder in place in the jacket 1 comprises an outstanding annular flange 5 upon one end of the cylinder arranged to engage an inwardly-

extending annular flange 6 formed in the adjacent end of the jacket 1. A head 7 closes the said ends of the jacket and cylinder, said head being held in place by means such as screw studs 8 engaging said head and the jacket 1. The head 7 may have suitable inlet and exhaust passages 9 and 10 therein, and said passages may be controlled by any suitable valve mechanism. Within the head 7 is a chamber 11 which is in communication at all times with the compartment 1^a in the interior of the jacket 1 through a plurality of passages 12 in the flange 6.

Positioned above the jacket 1 and secured thereto is a reservoir or convection chamber 13 which is open at its bottom and communicates with both of the compartments 1^a and 1^b.

A tank 14 preferably located in or upon the base 3 of the engine below the compartment 1^b communicates at its upper end with the compartment 1^b of the jacket 1. The lower end of said tank 14 is connected with the chamber 11 in the head 7 by pipes 15. 16 is a cock for draining the system of the cooling medium. The end of the jacket 1 opposite the head 7 fits closely about the cylinder 2, suitable packing 17 being inserted between the cylinder and the jacket in order to form a fluid-tight joint between said parts.

When the engine is running the explosion end 2^a of the cylinder 2 tends to become hotter than the other end. The cooling medium in the compartment 1^a of the jacket 1 is thereby heated and rises into the reservoir 13. This action causes a movement of the cooling medium in the tank 14 through the piping 15 into the chamber 11, directly against that portion of the head 7 which closes the end of the cylinder, and thence along the combustion end 2^a of the cylinder into the compartment 1^a of the jacket. From the reservoir 13 the cooling medium flows downwardly through the compartment 1^b of the jacket and into the tank 14, thus completing the circuit.

It will be seen that the cooling medium is first drawn into the chamber 11 in the head 7 where it cools not only the head of the cylinder but also the fuel inlet and exhaust valve mechanism. By cooling the combustion end 2^a of the cylinder more than the other end, said end 2^a is prevented from

expanding more than the other end, and the piston therefore fits the cylinder fluid-tightly at all points. When the combustion end of the cylinder is heated to a higher 5 temperature than the other end, the piston also expands unduly and hence fits the cooler end of the cylinder so tightly that the lubricant is driven before the piston to a point where it is of no use, the result of which 10 is that the piston is insufficiently lubricated, moves with excessive friction, heats the parts, wears rapidly, and unnecessarily consumes power. By using the cooling system herein disclosed these disadvantages are entirely eliminated.

I would have it understood that I do not limit myself to the construction herein disclosed, for various modifications will occur to those skilled in the art.

20 I claim as my invention:

1. In an engine cooling system, in combination, a jacket arranged to surround the engine cylinder, said jacket having two compartments therein; a container positioned 25 above said jacket and communicating with both of said compartments; and a second container below said jacket and communicating with both of said compartments.

2. In an engine cooling system, in combination, a jacket arranged to surround the engine cylinder; a partition dividing said jacket into two compartments; a reservoir positioned above said jacket and being in communication with both of said compartments; a tank below the jacket and communicating at its upper end with one of said compartments; and a connection between the lower end of said tank and the other compartment.

3. In an engine cooling system, in combination, a jacket arranged to surround the engine cylinder and comprising two separate compartments; a head closing one end of said jacket, said head having a chamber 45 therein communicating with one of said compartments; a convection chamber connecting said compartments; and means connecting the other of said compartments with the chamber in said head.

4. In an engine cooling system, in combination, a jacket arranged to surround the engine cylinder and comprising two separate compartments; a head closing one end of said jacket and the adjacent end of said 55 cylinder, said head carrying valve mechanism and having a chamber therein; a convection chamber connecting said compartments; means connecting one of said compartments with the chamber in said head and means 60 connecting the other of said compartments with the chamber in said head.

5. In an engine cooling system, in combination, a jacket arranged to surround the engine cylinder; a partition dividing said 65 jacket into two compartments, one end of

said jacket fitting tightly about the cylinder; a head closing the opposite end of said jacket and the adjacent end of said cylinder, said head having a chamber therein communicating with one of said compartments; a reservoir positioned above the jacket and communicating with both of said compartments; a tank below said jacket and communicating with one of said compartments; and a connection between said tank and the 75 chamber in said head.

6. In an engine cooling system, the combination with an engine base, of a jacket mounted thereon and comprising two compartments, an engine cylinder removably supported in said jacket, one end of said jacket fitting tightly about said cylinder, the other end of said jacket having an inwardly-extending annular flange fitting about said cylinder, said flange having a 85 plurality of passageways therethrough, an outstanding annular flange on said cylinder engaging said inwardly-extending flange, a head closing the end of the jacket and cylinder adjacent said flanges and holding the 90 flange on the cylinder against the flange on the jacket, said head having a chamber therein, the passageways in said inwardly-extending flange connecting said chamber with one of said compartments, a convection chamber 95 outside of the jacket connecting the two compartments, and means connecting the other of said compartments with the chamber in said head.

7. In an engine cooling system, in combination, a jacket arranged to surround the engine cylinder; a partition dividing said jacket into a forward compartment and a rear compartment disposed in the same horizontal plane; a chambered head communicating with the explosion end of the forward compartment; means connecting the lower part of the rear compartment with the lower part of the chambered head; and a convection chamber connecting the upper parts of 105 said compartments.

8. In an engine cooling system, in combination, a jacket arranged to surround the engine cylinder; a partition dividing said jacket into a forward compartment and a 115 rear compartment disposed in the same horizontal plane; a convection chamber positioned above said jacket and communicating at its lower end with the upper portions of said compartments; a tank below said compartments and communicating at its upper end with the lower part of the rear compartment; and means connecting the lower part of the tank with the lower part of the explosion end of the forward compartment. 120 125

THORMOD ODEE.
